(57) **CLAIM**

The ornamental design for a control panel for a mobile phone and/or car or other vehicular handsfree device, as shown and described.

DESCRIPTION

FIG. 1 is a front perspective view of a control panel for a mobile phone and/or car or other vehicular handsfree device showing my design;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.
